(57) **CLAIM**

The ornamental design for a container having a metal container closure as shown and described.

DESCRIPTION

FIG. 1 is top perspective view of a container, which includes the metal container closure of FIG. 1;

FIG. 2 is a top elevation view of the container having a metal container closure of FIG. 1;

FIG. 3 is a front-side elevation view of the container having a metal container closure of FIG. 1;

FIG. 4 is a rear-side elevation view of the container having a metal container closure of FIG. 1;

FIG. 5 is a left-side elevation view of the container having a metal container closure of FIG. 1;

FIG. 6 is a right-side elevation view of the container having a metal container closure of FIG. 1; and,

FIG. 7 is a bottom plan view of the container having a metal container closure of FIG. 1.

In the drawings, the broken lines depict portions of the container having a metal container closure that form no part of the claim.

1 Claim, 7 Drawing Sheets
